[57] CLAIM

The ornamental design for combined cover and stand for electric light, substantially as shown and described.

DESCRIPTION

FIG. 1 is a plan view of combined cover and stand for electric light showing my new design;

FIG. 2 is a front elevational view thereof;

FIG. 3 is a right side view thereof;

FIG. 4 is a rear elevational view thereof;

FIG. 5 is a perspective rear view thereof;

FIG. 6 is a perspective view of the combined cover and stand in use as a cover, the light being shown in broken lines for illustrative purposes only; and

FIG. 7 is a perspective view of the combined cover and stand in use as a stand, the light being shown in broken lines for illustrative purposes only.

FIG. 1

FIG. 2

FIG. 3

FIG. 4

FIG. 5

FIG. 6

FIG. 7
